SUPPORTING FABRICATION FOR TENTS

John W. Dixon and Paul A. Filer, Waco, Tex.,
assignors of one-third to Francis M. Compton
and Reed Compton, Waco, Tex.

Application November 20, 1933, Serial No. 698,736

5 Claims. (Cl. 135—4)

This invention relates to tents and it has particular reference to tents and canopies where-in supporting fabrication within the confines thereof are dispensed with.

5 The principal object of the invention is to provide a tent which is particularly useful as a protective covering for graves during interment of deceased persons, religious gatherings and the like, especially where a central supporting pole or like structure is objectionable.

Another object of the invention is to provide a supporting structure for tents, while not only making the central supporting structure unnecessary, increases the wind resistance of the 15 tent, enhances the appearance of the structure and generally improves upon the conventional reinforcing fabrication of a tent, as a temporary shelter or covering especially.

Another object of the invention is to provide 20 a support of the character specified which may be erected in a minimum of time by a single individual, requiring no tools of a complicated nature and due to its novel construction, may be disassembled and stored in a comparatively 25 small space. These features are such as to render the invention applicable for use by morticians especially and in other cases where speed in erection and durability are prime factors, combined with the fact that no central supporting 30 devices are present to interfere with the services or movements under the tent.

Still another object of the invention is to provide means to effect adjustment of the invention to conform with the design of ready 35 made canopies or tent coverings, thus enabling those possessing tents to replace the objectionable supporting structure with a structure having no annoying center supporting post.

With the foregoing objects as paramount, the 40 invention has particular reference to its salient features of construction and arrangement of parts which will become manifest as the description proceeds, taken in connection with the accompanying drawings, wherein:—

45 Figure 1 is a perspective view of a tent supporting fabrication constructed according to the present invention.

Figure 2 is a detail view in perspective of an 50 adjustable spacing member employed to retain the side ribs of the structure in fixed position.

Figure 3 is a detail view in perspective of one 55 of the retaining members for the spacing member shown in Figure 2.

Figure 4 is a slightly modified form of the

embodiment shown in Figure 1, showing the provision for ridge length adjustment.

Figure 5 is a fragmentary detail view of one 60 of the hinged joints between the side rib and supporting post.

Figure 6 is a perspective view of a further modified form, showing the adaption of the invention in the erection of a tent having a pyramidal or of A design, and

Figure 7 is a fragmentary detail view of a 65 form of reinforcing rib for the slope of the tent in alignment with the ridgepole.

Continuing with a more detailed description of the drawings, reference is primarily made to Figure 1, wherein is shown in skeleton form a 70 supporting fabrication embodying the elements of the present invention. In this figure, 1 designates a preferably tubular member adapted to supplant the conventional wooden ridgepole. Midway between the ends of this member is 75 welded or otherwise secured a hinge 2, either formed upon or joined to a pair of tubular arms 3. As apparent, the arms 3 are adapted to extend outwardly and downwardly from either side of the member 1 and on the same 80 angular plane.

Into the ends of the tubular arms 3 are inserted rib rails 4 of wood or other suitable material. These rails are hinged at their extremities at *a* to the normally perpendicular poles 5, 85 which support the sides of the tent and which are adapted to fold upon the rails 4 when the structure is dismantled.

While it is not considered absolutely essential, a hook 6 is provided and secured to the 90 rail at *b* on the rail 4, to engage an eyelet *c*, screwed or otherwise suitably secured to the pole 5. This arrangement is particularly shown in the fragmentary view, Figure 5.

A substantially V-shaped reinforcing member 95 7 insures rigidity of the members 1 and 3 by having its free ends welded at *d* adjacent the ends of the member 1 and its central bend secured by means of the bolt 8 to a pair of co-operating bars 9, which function to retain the 100 arms 3 in fixed, angular relationship. A detail view of these bars is shown in Figure 2.

Since it is necessary that the angularity of the arms 3 be changed in cases where the pitch of a canopy varies, it follows that the relationship of the bars 9 with the arms 3 must be altered. This is accomplished through the medium of boxes 10 or other suitable means affixed in spaced relation to the ends of the arms 3 and into which the angularly bent ends 11 of the 110

bars 9 are inserted. This arrangement is such that the fixed relationship of the bars with the arms 3 may be changed to conform with the angularity of the arms as the latter are adjusted 5 to the pitch of the fabric covering, not shown.

To insure against displacement of the fabric on the supporting structure, perpendicularly arranged pins 12 are provided in the ends of the member 1, to extend through apertures in the 10 fabric. The ropes 13, shown in solid and dotted lines in Figure 1 are conventional.

As apparent in Figure 1, a chain 14 or other means is necessary to prevent spreading of the rails 4 and has its ends connected to eyelets 15, 15 suitably secured to the rails 4. These eyelets may be secured to sleeves designed to embrace the rails 4 if found more desirable, but in practice, the threaded shanks of conventional construction have been considered satisfactory.

20 Referring now to Figure 4, a modified view, it will be observed that there is little difference between the structure shown therein and that shown in Figure 1, except that the member 15 is capable of being extended by virtue of the 25 members 16 which are received in the ends of member 15. These members 16 carry the perpendicular pins 17, analogous to the pins 12 in Figure 1 and are secured against longitudinal displacement in member 15 by set screws 18 30 entering near the ends of the member 15 and engaging the members 16, as shown in Figure 4. The arms 19, hinged at 20 are unlike the structure illustrated in Figure 1 and are similarly held against relative displacement by adjustable 35 bars 21 as shown, whose positions with respect to the arms 19 are altered by virtue of the retaining boxes 22. A V-shaped reinforcing member 23 maintains true horizontal position of the member 15 as in the preceding case.

40 Referring to Figure 6, it will be noted that a structure is therein shown to support a tent of pyramidal design, in which the ropes, not shown, converge to a common point, where they are tied to a ring, also not shown, but 45 which ring encompasses the vertical pin 24, which latter, in turn is mounted upon the plate 25. The plate 25 is secured, by means of the brace 26 to one of the arms 27, hinged at 28 and held in spaced relationship by bars 29, similar to 50 bars 9 in Figure 2 and bars 21 in Figure 4.

It is pointed out that in order to simplify the method of securing the bars 9, 21 and 29 together, they are correspondingly corrugated as shown in the several figures.

55 To further strengthen the supporting structure shown in the several figures, an extra rail 30, shown in Figure 7, may be provided for the sides of the tent opposing the rails 4 shown in Figure 1. These auxiliary rails are employed 60 preferably in the type of tent for which the structure shown in Figure 1 is designed to support and comprises the rail 30, to one end of which is affixed an angular tip 31 designed to enter the open end of the member 1, and a tip 65 32, provided with an eyelet 33 or other suitable means to effect its securement to the vertical post or pole 34, adapted to be placed intermediate the corner poles 35 in Figure 1.

It is apparent from the foregoing that the 70 structure embodying the invention may be

erected in a very short period of time compared to the time required to pitch a tent of conventional design and that this may be done by a single person without difficulty. Also, it should be apparent that a tent so erected will have all of the prerequisites of a tent of ordinary design but from which is omitted the annoying center pole.

Manifestly, the construction shown is capable of considerable modification and such modification as is considered within the scope and meaning of the appended claims is also considered within the spirit and intent of the invention.

What is claimed is:

1. A tent supporting structure including a ridge member and a pair of tubular side members hinged together and secured at their fulcrum point to said ridge member intermediate its ends, a pair of side poles, rails having hinged connection at one end with the upper ends of said poles and having their opposite ends extended into said tubular side members and means for holding said latter members in fixed angular planes.

2. A supporting fabrication for tents and the like including a ridge member and a pair of tubular side members hingedly secured thereto and extending outwardly and downwardly, side rails having their ends extended into said tubular side members, a pair of poles whose upper ends are hinged to the free ends of said side rails, extensible means holding said tubular members in adjusted positions and means connected to said ridge member and said extensible means for holding said ridge member rigid with respect to said tubular side member.

3. A supporting fabrication for tents and the like, including a pair of tubular members having their ends hinged together and defining a substantially V-shape when in operative position, a pair of rails having their ends extended into said tubular members, supporting poles whose upper ends are hinged to the free end of said rails and means for holding said tubular members in adjusted positions.

4. A supporting fabrication for tents and the like including hinged members arranged in inverted V-shape to support the roof of the tent, an extensible ridge member connected to the fulcrum point of said first member, means to rigidify said members with respect to one another and collapsible means for supporting said members.

5. A supporting fabrication for tents and canopies including a pair of members arranged in inverted V-shape formation and hinged together for angular displacement, an extensible ridge member connected intermediate its ends to the fulcrum point of said first members, an extensible bracing member connected to and extending between said hinged members for retaining the same in adjusted positions, collapsible means for supporting said members from points equidistantly spaced from the longitudinal axis of said ridge member and means extending between said supporting means to prevent outward movement thereof.
